UNITED STATES PATENT OFFICE

GEORGE W. JANDA, OF BISMARCK, AND ROBERT C. PLAGGMIER, OF TAYLOR, NORTH DAKOTA, ASSIGNORS TO THE NATIONAL SURVAULT COMPANY, OF BISMARCK, NORTH DAKOTA, A CORPORATION

BURIAL VAULT

Application filed November 17, 1928. Serial No. 320,092.

This invention relates to burial vaults, and particularly to that type of surface burial vault having therein a sealed casket chamber and a sealed dead air chamber above the casket chamber for insulating the same.

It is an object of this invention to provide a novel and improved seal in such a burial vault construction for the dead air insulating chamber, and it is a further object to provide a novel and improved seal in such a construction for the casket chamber.

It is yet another object of the invention to provide certain novel improvements on the invention of Robert C. Plaggmier, disclosed and claimed in his United States Patent No. 1,663,464, issued March 20, 1928.

These and other objects and advantages of the present invention will more fully appear from the following description, made in connection with the accompanying drawings, wherein like reference characters refer to the same or similar parts throughout the two views, and in which,

Fig. 1 is a view in side elevation of the burial vault assembled in position for use in the ground, certain of the parts being broken away and shown in longitudinal vertical section, and

Fig. 2 is a vertical section taken on the line 2—2 of Fig. 1, as is indicated by the arrows.

Referring to the drawings, a substantially rectangular box 3 is provided, molded preferably from reinforced concrete and including a bottom and side and end walls, the top of the box being open. The side and end walls of the box project straight upwardly from the bottom of the box for some little distance and are then slightly outwardly offset to form a continuous inwardly and upwardly projecting lower shoulder or ledge 4, whereupon the outer side and end walls project again straight upwardly. The inner side and end walls from the ledge 4 incline diagonally upwardly and inwardly for some little distance until they project inwardly preferably the same distance as do the portions of the end and side walls projecting upwardly immediately from the bottom of the box. Diagonally and upwardly extending portions of the side and end walls may be designated 5, and these portions of the walls terminate in an inwardly and upwardly projecting shoulder or ledge 6. From the ledge 6, the inner surfaces of the side and end walls of the box project straight upwardly and the side and end walls at their upper edges are inwardly beveled at 7. A very short distance above the upper ledge 6, rounded grooves 8 are formed in the side and end walls of the box which project outwardly from the interior of the box into the inner surfaces of the end and side walls.

In use for a burial, a box will be situated within a grave, such as the grave 9, so that the upper edges 7 of the side and end walls will extend close to the level of the ground, but preferably a little below the same as is indicated in the drawings. The box is then ready for the reception of the casket, such as the casket 10, indicated in dotted lines Fig. 2. The casket is lowered in the box so that the same rests on the bottom thereof. Formed slabs 11 are then lowered into the box and they are of such size that they will fit and rest on the lower ledge 4. Each slab 11 is half the length of the interior of the box from between the ends of the box above the ledge 4, and each slab is arched both longitudinally and transversely as is illustrated, the longitudinal arched portion forming merely a half arch. In placing the slabs 11 on the lower ledge 4, one side edge of one of the slabs will first be lowered into place so that it rests on one side of the ledge 4, whereupon the other and unlowered edge of the slab will be downwardly swung about the first lowered edge as a pivot point until the last mentioned edge rests on the other side of the ledge 4. The slab 11 will then be slid along the ledge 4 until the end of the slab abuts one of the end walls of the vault. The second slab 11 will be similarly lowered into position on top of the first slab 11, whereupon the second slab will be slid towards the unoccupied end of the vault until the same rests in place on the ledge 4, with one end of the slab abutting the hitherto unoccupied end wall of the vault. The formed slabs 11 will thus close the top of a casket chamber 12.

formed at the lower portion of the box 3 and defined by the bottom of the box, and the portions of the inner side and end walls of the box projecting upwardly from the bottom of the ledge 4. After the slabs 11 have been properly placed in the box 12, a molten layer 13 of concrete is poured over the tops of the slabs 11 to completely cover the slabs 11 and to project upwardly along the diagonally inclined inner walls 5 of the box for a short distance. The layer 13 will form an air tight and moisture proof seal for the casket chamber 12, and due to the upper and inward inclination of the inner surfaces 5 of the side and end walls of the box, the layer 13 cooperating with the surfaces 5 will form a wedge-like seal which can never be removed without completely breaking up the poured layer 13 even though the joint between the edge of the layer 13 and the inclined surfaces 5 of the walls is broken.

Slabs 14 corresponding in shape and size to the slabs 11, are placed on the upper ledge 6 after the layer 13 has been poured, to close the top of a dead air insulating chamber 15 defined by the top of the layer 13, and the inclined inner surfaces 5 of the side and end walls extending from between the layer 13 to the ledge 6. A layer 16 of molten concrete is then poured over the slabs 14 and this layer will run into the grooves 8 to completely fill the same, while at the same time completely covering the slabs 14. The layer 16 will extend upwardly to the tops of the inner side surfaces of the end and side walls of the box, and it will form an air tight and moisture proof seal for the dead air chamber 15. Due to the fact that the poured layer 16 projects into the grooves 8 in the side and end walls, the layer 16 can never be removed to permit of access to the dead air chamber 15 without completely breaking the layer 16. While the layer 16 is still in molten condition, a formed cover slab 17 is placed over the top of the box to completely close the top and to rest on the layer 16 and on the beveled edges 7. The cover slab 17 has embedded therein and projecting downward therefrom a number of concrete reinforcing members 18 which are preferably of U-shape, and the major portion of these reinforcing members will be embedded within the poured layer 16 to tightly bind the cover slab 17 to the layer 16. The lower side edges of the cover slab 17 are beveled to fit on the beveled upper edges 7, and the top of the cover slab 17 will be finished off in any suitable attractive design. If desired, a head plate 19 may be molded integral with the cover slab 17. The cover slab 17 will preferably be rabbeted at its upper side edges and this rabbeted portion will be preferably laid flush with the ground as is illustrated in Fig. 1, so that a lawn mower can be run on top of the rabbeted

portions to trim the grass at the sides and ends of the vault.

When the vault is installed, the dead air chamber 15 will act as an insulating chamber above the casket chamber 12. The slabs 14, layer 16 and cover slab 17, together with the upper portions of the end and side walls of the box 3, will form a heavy and thick structure at the top of the vault which will very largely absorb the direct rays of the sun, and prevent the air in the dead air chamber 15 from heating up to any great extent. The dead air chamber 15 will form an additional insulating means to prevent the casket in the casket chamber 12 from being affected by outside weather conditions. Also the construction at the top of the vault being very heavy and strong will effectively resist the heaving of the ground from frost or other causes, and thus prevent the seal formed by the poured layer 16 and the seal formed by the poured layer 14 from being broken. The cover slab 17, poured layer 16, formed slabs 14 and the upper portions of the walls of the box will be effectively bound together to prevent entrance into the vault when once sealed up. The cover slab 17 and poured layer 16 will be incapable of removal, even though for any reason the joint between the poured layer 16 and the side and end walls of the vault is broken, due to the fact that the poured layer 16 projects into the grooves 8. The corpse in the casket chamber will keep indefinitely in the vault and there is no possibility that the vault will ever be molested. When the box 3 is molded, iron forms are preferably used which will form a concrete surface impervious to air and water.

It will, of course, be understood that various changes may be made in the form, details, arrangement and proportions of the various parts without departing from the scope of the present invention, which generally stated, consists in the matter shown and described and set forth in the appended claims.

What is claimed is:

1. A sealing joint for a burial vault of the surface type having side and end walls, shoulders on said walls projecting inwardly therefrom and defining upper and lower portions of said vault, formed members resting on said shoulders and acting as a closure for the lower portion of said vault, outwardly projecting grooves in said side and end walls immediately above said formed members, and a poured layer of concrete on said formed members entering and filling said grooves and sealing the vault.

2. The invention as defined in claim 1 wherein said formed members are arched transversely and longitudinally.

In testimony whereof we affix our signatures:

GEORGE W. JANDA.
ROBERT C. PLAGGMIER.
